UNITED STATES PATENT OFFICE.

GEORGE RADFORD, OF OAKLAND BEACH, RHODE ISLAND, ASSIGNOR TO RICHMOND
LACE WORKS, OF ALTON, RHODE ISLAND, A CORPORATION OF MAINE.

DESIGN FOR LACE.

Application filed February 5, 1926. Serial No. 16,411. Term of patent 7 years.

To all whom it may concern:

Be it known that I, GEORGE RADFORD, a citizen of the United States, residing at Oakland Beach, in the county of Kent and State of Rhode Island, have invented a new, original, and ornamental Design for Lace, of which the following is a specification, reference being had to the accompanying drawing, forming part thereof, wherein the single figure is a plan view of a piece of lace illustrating my new design.

I claim:

The ornamental design for lace as shown.
GEORGE RADFORD.
